(57) **CLAIM**

The ornamental design for a folding shelf, as shown and described.

DESCRIPTION

FIG. 1 shows a perspective view of the folding shelf, showing my new design.

FIG. 2 shows a right side elevation view thereof.

FIG. 3 shows a left side elevation view thereof.

FIG. 4 shows a front elevation view thereof.

FIG. 5 shows a rear elevation view thereof.

FIG. 6 shows a top plan view thereof.

FIG. 7 shows a bottom plan view thereof.

FIG. 8 shows an alternate perspective view thereof, with the folding shelf in a partially folded configuration; and, FIG. 9 shows an alternate perspective view thereof, with the folding shelf in a fully folded configuration.

1 Claim, 7 Drawing Sheets(56)
